FIG. 1 is a front elevational view of a wall mounted jar wrench showing my new design, with the jaws in depending position;

FIG. 2 is a rear elevational view thereof;

FIG. 3 is a left side elevational view thereof;

FIG. 4 is a left side elevational view with the jaws in raised position;

FIG. 5 is a plan view taken from the top of FIG. 1;

FIG. 6 is an elevational view taken from the right of FIG. 4;

FIG. 7 is a front elevational view of a wall mounted jar wrench showing another form of my new design, with the jaws in depending position;

FIG. 8 is a rear elevational view;

FIG. 9 is a side elevational view with the jaws in raised position;

FIG. 10 is an elevational view taken from the right of FIG. 9; and

FIG. 11 is an enlarged fragmentary perspective view of the right hand jaw in FIG. 8.

This is a continuation-in-part of my earlier filed application Ser. No. D.292 of Dec. 22, 1965, now abandoned.

I claim:

The ornamental design for a wall mounted jar wrench, as shown and described.
